CLAIM

I claim the ornamental Design for a microphone body with actuator button, as shown and described.

DESCRIPTION

FIG. 1 is a perspective view of a first embodiment of the microphone body with actuator button;

FIG. 2 is a first side view of the microphone body with actuator button of FIG. 1;

FIG. 3 is a second side view of the microphone body with actuator button of FIG. 1, opposite the side shown in FIG. 2;

FIG. 4 is a third side view of the microphone body with actuator button of FIG. 1;

FIG. 5 is a fourth side view of the microphone body with actuator button of FIG. 1, opposite the side shown in FIG. 4;

FIG. 6 is a top view of the microphone body with actuator button of FIG. 1;

FIG. 7 is a bottom view of the microphone body with actuator button of FIG. 1;

FIG. 8 is a perspective view of a second embodiment of the microphone body with actuator button;

FIG. 9 is a first side view of the microphone body with actuator button of FIG. 8;

FIG. 10 is a second side view of the microphone body with actuator button of FIG. 8, opposite the side shown in FIG. 9;

FIG. 11 is a third side view of the microphone body with actuator button of FIG. 8;

FIG. 12 is a fourth side view of the microphone body with actuator button of FIG. 8, opposite the side shown in FIG. 11;

FIG. 13 is a top view of the microphone body with actuator button of FIG. 8; and,

FIG. 14 is a bottom view of the microphone body with actuator button of FIG. 8.

The broken lines are for illustrative purposes only and forms no part of the claimed design.
